POTTERY SETTER

Fred V. Wind, Los Angeles, Calif., assignor to
 Pacific Clay Products Company, Los Angeles,
 Calif., a corporation of California

Application April 7, 1941, Serial No. 387,273

5 Claims. (Cl. 25—153)

This invention relates to the art of firing ceramic ware in kilns and in particular to a pottery setter.

One of the objects of my invention is to provide a support for pottery during firing. Another object is to provide support elements for pottery which may be stacked in intercommunicating assemblies. Still another object is to provide a supporting ring for the rims of pottery articles which prevents distortion during firing. Another object is to provide a rim support which serves to equalize the openings of fired pottery articles. Another object is to provide a pottery setter which conserves kiln space.

These and other objects are attained by my invention which will be described in detail below, reference being had to the accompanying drawing which forms a part of this specification, in which:

Fig. 1 is a plan view of an assembly of pottery setters showing one form of my invention;

Fig. 2 is a cross-sectional view taken on the line 2—2 of Fig. 1;

Fig. 3 is a vertical sectional view partly in elevation showing another form of my invention;

Fig. 4 is a plan view of a single setter as used in the assembly of Fig. 3.

Referring to the drawing, fired ceramic ware support elements 11 have an outer portion 12, usually cylindrical, with means on the upper and lower edges to engage and align the individual elements into vertical assemblies as shown in Figs. 2 and 3. In Figs. 1 and 2, the engaging and aligning means consists of a tongue 13 on the upper edge and a corresponding groove 14 on the lower edge of the outer cylindrical portion 12. The tongue and groove elements may, of course, be reversed if desired. A "bell and spigot" joint may also be used between the setter elements. As shown in Figs. 3 and 4, the lower edge of the cylindrical portion 12 is off-set inwardly to form the seat 15 in which rests the upper edge 16 of the next lower setter element. Extending inwardly from the inside wall of the outer portion 12 of the support or setter, is an integral ledge 17 upon whose top surface is provided a raised edge or bead 18, forming a circular template which is adapted to extend slightly into the lip of the ceramic article being supported for firing. The top surface of the ledge is preferably level and smooth, except for this raised edge 18, so that, as the mouth of the ceramic article contracts in firing, it is not restrained until it contacts the raised edge 18, which then holds the mouth or lip to the desired symmetrical shape and size. The burned articles are therefore more uniform in size

of opening, and are less distorted than they usually are if not thus supported.

The particular assembly shown in Figs. 1 and 2, is especially designed for the firing of cups 19 with handles 20. In order to conserve space, as well as extra weight of kiln furniture, the handles are allowed to protrude through slots 21 made in the outer portion of the setters above the supporting ledge.

Additional savings in the weight of kiln furniture or setters, and in increased productive space in the kiln, when nestable ware is being fired, may be attained by making the outer portion 12 of my setters of less height than the height of the ceramic article to be fired. This is shown in Fig. 3, in which bowls 19a are set, inverted, upon the ledges 18, with the bottom part of each bowl extending upwardly through the opening of the ledge of the superposed setter, within the bowl supported by its ledge. This permits firing more ceramic articles in a stack of given height, and increases the efficiency of the operation and the output of the equipment, as well as providing support means which reduce the rejections of burned ware because of distortion and unequal shrinkage.

The ceramic support elements, or setters, are of course, previously fired, and their composition is selected to permit use at the temperatures required for firing the bisque or pottery articles. They may be made by jiggering, casting, pressing, or by other suitable methods.

After the firing, the assemblies of setters and fired articles are taken apart, and the setters may be reused.

While I have shown and described preferred embodiments of my invention, it is clear that it may be carried out with various modifications and changes, and I do not wish to be restricted except as required by the prior art and the spirit of the appended claims.

I claim:

1. In a vertically aligned assembly of a plurality of superposed ceramic ware support elements and a plurality of unfired bowl-like ceramic articles, a ceramic ware support element comprising an outer portion defining a space to contain said article, said outer portion having means on its top and bottom edges to engage and align it with similar elements above and below it in the assembly, and said outer portion also having an integral ledge extending inwardly from its inner wall adapted to support the inverted article on its lip, said ledge being provided with an integral raised ring edge on its top surface adapted to project into the mouth of the

ceramic article and to closely fit said mouth at the maturing temperature whereby to hold its lip to prevent unsymmetrical shrinkage thereof during firing.

2. In a vertically aligned assembly of a plurality of superposed ceramic ware support elements and a plurality of unfired bowl-like ceramic articles adaptable for at least partial nesting, in which assembly each article is partly enclosed in two adjacent elements, a ceramic ware support element comprising an outer portion defining a space to encompass said article but of less height than the ceramic article, said outer portion having means on its top and bottom edges to engage and align it with similar elements above and below it in the assembly; and said outer portion also having an integral ledge extending inwardly from its inner wall adapted to support the inverted article on its lip, said ledge being provided with an integral raised ring edge on its top surface adapted to project into the mouth of the ceramic article and to closely fit said mouth at the maturing temperature whereby to hold its lip to prevent unsymmetrical shrinkage thereof during firing.

3. In a vertically aligned assembly of a plurality of superposed ceramic ware support elements and a plurality of unfired bowl-like ceramic articles adaptable for at least partial nesting, in which assembly each article is partly enclosed in two adjacent elements, a ceramic ware support element comprising an outer portion defining a space to encompass said article but of less height than the ceramic article, said outer portion having means on its top and bottom edges to engage and align it with similar elements above and below it in the assembly; and said outer portion also having an integral ledge extending inwardly from its inner wall adapted to support the inverted article on its lip, the inside diameter of said ledge being great enough to permit the article partly contained in the support below to protrude therethrough, said ledge being provided with an integral raised ring edge on its top surface adapted to project into and closely fit the mouth of the ceramic article and to closely fit said mouth at the maturing temperature whereby

to hold its lip to prevent unsymmetrical shrinkage thereof during firing.

4. In a vertically aligned assembly of a plurality of superposed ceramic ware support elements and a plurality of unfired bowl-like ceramic articles adaptable for at least partial nesting, in which assembly each article is partly enclosed in two adjacent elements, a ceramic ware support element comprising an outer portion defining a space to encompass said article but of less height than the ceramic article, said outer portion having means on its top and bottom edges to engage and align it with similar elements above and below it in the assembly; and said outer portion also having an integral ledge extending inwardly from its inner wall adapted to support the inverted article on its lip, the inside diameter of said ledge being great enough to permit the article partly contained in the support below to protrude therethrough, said ledge having an integral raised edge on its top surface adapted to project into and closely fit the mouth of an inverted bowl-like ceramic article whereby to prevent unsymmetrical shrinkage of said ceramic article.

5. In a vertically aligned assembly of a plurality of superposed fired ceramic ware support elements and a plurality of unfired bowl-like ceramic articles adaptable for at least partial nesting, in which assembly each article is partly enclosed by two adjacent elements, a ceramic ware support element comprising an outer cylindrical portion defining a space of greater diameter and less height than the ceramic article, said outer portion at its top edge being offset to form a telescoping joint with the outer portion of the support element next above, and having an integral ledge extending inwardly from said cylindrical portion from a position above the telescoping joint with the support element immediately below, said ledge having an integral raised edge on its top surface adapted to project into and closely fit the mouth of said inverted bowl-like ceramic article whereby to prevent unsymmetrical warpage of said ceramic article.

FRED V. WIND.
